UNITED STATES PATENT OFFICE.

JOHN C. GRAHAM, OF PHILADELPHIA, PENNSYLVANIA.

DESIGN FOR GIMP.

SPECIFICATION forming part of Design No. 11,958, dated August 31, 1880.

Application filed June 4, 1880. Term of patent 7 years.

To all whom it may concern:

Be it known that I, JOHN C. GRAHAM, of the city and county of Philadelphia, in the State of Pennsylvania, have invented and produced a new and original Design for Gimp, of which design the following is a specification.

The accompanying drawing exhibits a face view of a pattern of gimp embodying and illustrating my design, which consists of a gimp having scalloped edges formed by the transverse returns of heavy or coarse weft-threads *a*, fine warp-threads *b*, woven over and covering the major portion of the weft-threads, and a central ornamentation formed by a continuous strand or strands of chenille or analogous material, *c*, which crosses and recrosses the warp-threads continuously from end to end of the gimp, being secured by being passed under warp-threads at such intervals as may be necessary to hold it firmly thereto. The raised ornamentation *c* traverses the gimp in a con-

nected series of adjoining parallel inclines, analogous to a rope or helically-twisted cord, covering, to a greater or less extent, the central portion of the warp-threads, and giving a uniform raised or plush effect, in the form shown, throughout the entire length of the gimp.

I claim—

The within-described design for a gimp having heavy transverse weft-threads, light warp-threads, and a raised ornamentation formed by a strand or strands of chenille or analogous material, said ornamentation extending continuously over the warp-threads in a connected series of adjoining parallel inclines, substantially as set forth.

J. C. GRAHAM.
